UNITED STATES PATENT OFFICE.

WILLIAM A. GOODMAN, OF LOS ANGELES, CALIFORNIA.

ELECTRIC HEATER.

Application filed December 27, 1923. Serial No. 682,859.

To all whom it may concern:

Be it known that I, WILLIAM A. GOODMAN, a citizen of the United States, residing at Los Angeles, in the county of Los Angeles and State of California, have invented new and useful Improvements in Electric Heaters, of which the following is a specification.

The general purpose of my invention may be inferred from the title thereof; but it is a special object of this invention to provide an electric heater comprising a composition body and made in standard sizes, some of which may be suitable for insertion within the walls of living-rooms, or the like, and between the studding thereof, while other forms may be provided on all sides with an external metallic or other casing, and optionally with legs, or with other features of construction suitable to portable heaters, to be sold as separate articles of commerce and used in any position desired.

It is an object of this invention to provide electric heaters, or the like, with suitable means permitting not only an effective radiation of heat therefrom but also with means favorable to a continuous or controlled circulation of air therethrough.

It is an object of my invention to provide an electric heater with a floor plate comprising a major or outlet opening and a minor or inlet opening arranged below the same, each of the mentioned openings being preferably provided with a grid, or its equivalent, adapted to prevent accidental contact of clothing or the like with an element heated by electric current.

It is a further object of my invention to provide a novel electric heater comprising a major or "radiator" recess and also a minor or air-feed recess, the latter being preferably below and parallel with the former, and separated therefrom by a web or partition provided with apertures or passages adapted to effect a favorable distribution of air advancing from the lower recess into the upper recess, as a result of convection; and the mentioned lower recess may optionally be provided additionally

with a valved inlet aperture extending 50 through the lower wall of the body of my electric heater in a manner permitting the delivery of cold air from an outside source therethrough.

It is a further object of this invention to 55 provide an electric heater comprising an insulating body and a front plate of the general character described with means for suitably spacing the mentioned elements apart and for retaining them in a desired 60 relationship; and my preferred construction for the purpose last referred to may comprise channel irons interposed between the mentioned insulating body and the mentioned front plate and also U-bolts, or the 65 like, preferably inserted in the mentioned body in such a manner as to serve not only for the reinforcement thereof but also for engagement, by means of nuts or the like threaded thereon, with the respective cor- 70 ners of a front plate.

Although the heating elements per se employed in my invention, need not be of novel character, my invention may comprise not only the structural elements above referred 75 to, and suitable incasing or supporting means which may optionally be associated therewith, but also a suitable reflecting plate, fitted within the mentioned major or radiator recess and suitably secured therein, 80 but also specific arrangements of conductive and nonconductive elements and apertures or retaining means therefrom, as hereinafter described.

Other objects of my invention will appear 85 from the following description of a form thereof suitable for use in the walls of a building and a form thereof suitable for sale and use as a portable article of commerce, taken in connection with the appended claims and the accompanying drawing, in which,

Fig. 1 is a vertical sectional view through an electric heater of my improved design showing the same as inserted in a wall, this 90 view being taken on a line 1—1 of Fig. 2.

Fig. 2 is a front view of a wall heater of the type shown in Fig. 1.

Fig. 3 is a view similar to Fig. 2 but showing parts broken away to exhibit a preferred interior construction.

Fig. 4 is a slightly enlarged horizontal 5 sectional view, which may be regarded as taken substantially on the line 4-4 of Fig. 1.

Fig. 5 is a detail view hereinafter referred to and showing a preferred mode of attaching my heating elements, these elements themselves being not necessarily novel in either their composition or mechanical structure.

Figs. 6 and 7 are respectively a front 15 view and a vertical section of a heater of the general type illustrated in the preceding figures but rendered portable by the provision of an outside casing and suitable supporting means.

20 Referring to the details of that specific embodiment of my invention illustrated in Figs. 1 to 5 inclusive, 1 may be a floor, and 2 may be the substantially vertical studs of a wall, the respective narrower vertical surfaces of the studs 2 being provided with lath and plaster or wallboard 3, 3' or a like coating, a conduit or pipe 4 being shown as extending upward from beneath the floor 1 in a manner permitting the optional introduction of fresh, cold air from without.

Coming now to the strictly novel features 35 of my invention, 5 may be a body of any preferred heat insulating composition, this composition being also preferably a poor conductor of electricity. This body may advantageously be formed of a plastic mixture of known type, and my preferred mixture for the purpose referred to contains Portland cement, or other hydraulic cement, admixed with diatomaceous earth and sufficient water to impart a suitable degree 40 of plasticity, this plastic composition, or its equivalent, being preferably molded in advance and permitted to set and harden 45 into one of a number of stock sizes, suitable for use in walls of any usual thickness or type, the body 5 being in any case preferably provided not only with a major or radiator recess 6, in the upper portion thereof, but also with a second and minor air-feed recess 7, separated therefrom by means 50 such as web or partition 8, shown as provided with a plurality of substantially vertical and parallel air distributing passages 9.

By the means referred to or their equivalent 55 my novel electric heater may be provided with means permitting not only a distribution of heat by radiation but also with means favorable to the distribution of heat by convection, cold air being permitted to enter the air-feed chamber 7 and to rise therefrom into contact with heating elements of any preferred character positioned in the major recess 6; and, in embodiments of my

invention chosen for purposes of illustration, the block 5 may also be provided with a substantially vertical channel or opening 9^a shown as extending from beneath the same into the air-feed recess 7, this passage 9^a being adapted to cooperate with the conduit 4, when such is employed, in the introduction of fresh air from an outside source,—materially contributing to the suitable ventilation of a room in whose wall or 75 walls a heater of the type referred to may be employed.

In the casting of a body 5 of the general character described, I may advantageously provide not only for the recesses and conduits above referred to but also for the suitable attachment of a front plate and heating units thereto, and my preferred means for the purposes last referred to may comprise bolts or screws 10, originally provided 80 not only with heads 11 or their equivalent but with washers 12, the elements here referred to being embedded in such manner as to bring the outer surfaces of the mentioned washers flush with the surface 13 through 85 which the screws 10, or their equivalent, may project substantially at right angles.

Although means similar to those just described might optionally be employed for the retention of a front or register plate 14, or its equivalent, I consider it advantageous to employ for the purpose last referred to means such as the bent rods or U-bolts 15, capable not only of cooperating with nuts 16, threaded thereon, in the retention of a front plate, but also capable of serving as an actual reinforcement of the block 5, through which they may advantageously extend in a vertical plane in the manner best illustrated in Figures 1 and 7. Although the front plate 14 may be of any preferred type, I consider it advantageous to employ a front plate of the general character shown in Figures 2 and 6, this plate being provided not only with a major aperture opposite the major or radiator recess in block 5, but also with a minor aperture 18 opposite the air-feed recess 7, the latter aperture being adapted to admit cool air laterally into said recess, from which it may rise, in the manner above indicated, through the distributing openings 9 thereabove and in contact with the heating elements in the radiator recess 6, in an obvious manner,—and both of the apertures 17 and 18 being preferably provided with grids or reticulated guards adapted to prevent accidental contact of clothing, or the like, with a heating element enclosed thereby. Especially when my novel electric heaters are to be enclosed 110 or incorporated in a wall, or the like, any suitable means may be provided for the spacing of a plate 14, or its equivalent, from a block 5, my preferred means for the purpose last referred to being channel irons 19,

130

20, which obviously may be selected with references to the thickness of a lath-and-plaster or wallboard construction in connection with which my novel heater is to be 5 employed.

Although the channel irons 19, 20 or their equivalent may optionally be provided on all four sides of the front of a heater of my novel design, it is of primary importance 10 that they extend across the top and bottom thereof, being preferably retained in their intended position by the threading of the outer or free ends of the bent rods or U-bolts 15 therethrough; and when my novel heater 15 is provided with a front plate having separate outlet and inlet apertures 17 and 18 or their equivalent, I may advantageously employ also an intermediate channel iron 21 or its equivalent shown as extending horizontally opposite the web or partition 8; and the channel irons 20 and 21 may optionally be apertured to receive and to provide bearings for a pin 22, carrying damper or valve 23, whose handle 24 may extend 25 outwardly through a slot 25 in the front plate 14,—to afford a ready means for control of the introduction of cold air from an outside source, or merely for the introduction of air through the mentioned aperture 29^a or its equivalent.

Although the radiator recess 6 may be of any preferred configuration, I consider it advantageous to provide the same with a bottom or back, the lower portion 26 of 35 which may be substantially vertical and parallel with the plate 12, although the upper portion 27 thereof may advantageously be forwardly inclined in a manner favorable both to the outward deflection of an air current and to the downward reflection of radiated heat, as best shown in Figures 1 and 7; and I may advantageously provide, within the radiator recess 6, not only heating element or elements 29, or their equivalent, but also a metallic or other heat-reflecting lining 30, which may advantageously be formed of polished sheet copper, or its equivalent, from which the heating elements 29, shown as retained by nuts 31 40 upon the mentioned screws 11, may be spaced by any suitable means such as washers or nuts 32, which may be formed of or associated with insulating material or material of low electrical conductivity,—similar nuts or washers 33 being optionally interposed between the heating elements 29 and the mentioned nuts 31.

As illustrated in Figures 6 and 7, instead of positioning my novel electric heater in a wall or the like, I may optionally incorporate the same in a portable unit. The insulating blocks 5, or their equivalent, being in any case formed in advance, and not "on the job" I may optionally surround the same 65 with a metallic or other casing, which may

be in the form of a substantially rectangular box 34, which may be provided with legs 35, of any preferred type, or with other supporting means, and which may correspond in its external dimensions to the outline of a front plate 14 to be used in connection therewith; and, although it will be obvious that a heater possessing many of the advantages of my described construction might be provided even without the use 70 of the channel irons 19, or their equivalent, when the latter are employed it will be obvious that the depth of the box 34 should be sufficient to accommodate not only the block 5 but the auxiliary and connecting elements referred to; and obvious also that, if wiring is to be carried through lateral apertures 36, shown as coincident with apertures 37 in the metallic or reflecting lining of the recess or chamber 6, corresponding lateral aperture or apertures may optionally be provided (at points not shown) in the substantially vertical sides of the enclosing casing 34.

The heating elements 29, or their equivalent, may be connected by any suitable means such as screws 38, shown as provided with nuts 39, these screws preferably projecting from the inner or hidden surfaces of the respective heating elements, for the conduction of electricity thereto; and the conductors may optionally be carried inward through one of the lateral openings 36 and outward through an opposite lateral opening, branches being preferably provided in such manner as to connect the heating elements, when a plurality of such elements are employed, in parallel rather than in series,—thereby adapting my heater to be used in any usual constant-potential electric 95 system.

Although I have herein described two complete embodiments of my invention, it will be understood that these are merely illustrative of the general scope and character of my invention, which may be carried in stock sizes suitable for interposition in walls of any usual or preferred type or provided in portable organizations of any required size, and also understood that various features of my invention might be independently employed and that various modifications might be made without the slightest departure from the spirit and scope of my invention as the same is indicated above and in the following claims:

What I claim is:

1. An electric heater comprising an upright body of insulating material, a recess formed in the side of said body, a partition formed in said recess adapted to define an air feed recess and a radiating recess, an electric heating element disposed in said radiating recess above said partition, and passages formed in said partition permitting 125 130

- air to pass through said partition from said air feed recess to said radiating recess.
2. An electric heater comprising an upright body of insulating material, a recess formed in the side of said body, a partition formed in said recess adapted to define an air feed recess and a radiating recess, an electric heating element disposed in said radiating recess above said partition, passages formed in said partition permitting air to pass through said partition from said air feed recess to said radiating recess, and an opening formed in the bottom of said body communicating with said air feed recess.
3. An electric heater comprising an upright body of insulating material, a recess formed in the side of said body, a partition formed in said recess adapted to define an air feed recess and a radiating recess, an electric heating element disposed in said radiating recess above said partition, passages formed in said partition permitting air to pass through said partition from said air feed recess to said radiating recess, an opening formed in the bottom of said body communicating with said air feed recess, and a damper in said opening.
4. An electric heater comprising an upright body of insulating material, a recess formed in the side of said body, a partition formed in said recess adapted to define an air feed recess and a radiating recess, an electric heating element disposed in said radiating recess above said partition, and passages formed in said partition permitting air to pass through said partition from said air feed recess to said radiating recess, said radiating recess being lined with a metallic casing.
5. An electric heater comprising an upright body of insulating material, a recess formed in the front face thereof, a partition formed in said recess defining a radiating recess and an air feed recess, an electric heating element disposed in said radiating recess, a cover plate secured to said body having apertures permitting heat to be radiated therethrough from said radiating recess, and other apertures permitting air to enter said air feed recess, there being openings formed in said partition permitting air to pass from said air feed recess to said radiating recess.
6. An electric heater comprising an upright body of insulating material, a recess formed in the front face thereof, a partition formed in said recess defining a radiating recess and an air feed recess, an electric heating element disposed in said radiating recess, a cover plate secured to said body having apertures permitting heat to be radiated therethrough from said radiating recess, other apertures permitting air to enter said air feed recess, there being openings formed in said partition permitting air to pass from said air feed recess to said radiating recess.
7. An electric heater comprising an upright body of insulating material, a recess formed in the front face thereof, a partition formed in said recess defining a radiating recess and an air feed recess, an electric heating element disposed in said radiating recess, a cover plate secured to said body having apertures permitting heat to be radiated therethrough from said radiating recess, other apertures permitting air to enter said air feed recess, there being openings formed in said partition permitting air to pass from said air feed recess to said radiating recess, and an additional opening formed in the bottom of said body communicating with said air feed recess whereby air may enter said air feed recess through the bottom of said body.
8. An electric heater comprising an upright body of insulating material, a recess formed in the front face of said body, a partition formed in said recess defining a radiating recess and an air feed recess, openings formed in said partition permitting air to pass from said air feed recess into said radiating recess, an electric heating element in said radiating recess, an opening formed in the bottom of said body permitting air to enter said air feed recess therethrough, and a damper for said opening.
9. An electric heater comprising an upright body of insulating material, a recess formed in the front face of said body, a partition formed in said recess defining a radiating recess and an air feed recess, openings formed in said partition permitting air to pass from said air feed recess into said radiating recess, an electric heating element in said radiating recess, an opening formed in the bottom of said body permitting air to enter said air feed recess therethrough, and a damper for said opening, said radiating recess being lined with a metallic casing.
10. An electric heater comprising an upright body of insulating material, a recess formed in the front face of said body, a partition in said recess defining an air feed recess and a radiating recess, openings in said partition permitting air to pass from said air feed recess into said radiating recess, means for admitting air to said air feed recess, bolts disposed in said radiating recess having their heads imbedded in said body, and electric heating elements mounted upon said bolts and held in spaced relation to said body.

11. An electric heater comprising an upright body of insulating material, a recess formed in the front face of said body, a partition in said recess defining an air feed recess and a radiating recess, openings in 5 said partition permitting air to pass from said air feed recess into said radiating recess, means for admitting air to said air feed recess, bolts disposed in said radiating re-

cess having their heads imbedded in said body, and electric heating elements mounted upon said bolts and held in spaced relation to said body, said radiating recess being lined with a metallic casing.

In testimony whereof I have signed my 15 name to this specification.

W. A. GOODMAN.
